STRAPLESS SLIP

Charles Schuster, Philadelphia, Pa.

Application August 28, 1948, Serial No. 148,350

Term of patent 7 years

(Cl. D3—26)

To all whom it may concern:

Be it known that I, Charles Schuster, a citizen of the United States, and a resident of Philadelphia, county of Philadelphia, State of Pennsylvania, have invented a new, original, and ornamental Design for a Strapless Slip, of which the following is a specification, reference being had to the accompanying drawings, forming a part thereof, wherein:

I claim:

The ornamental design for a strapless slip, substantially as shown.

CHARLES SCHUSTER.
